(57) **CLAIM**

The ornamental design for a push-to-close latch, as shown and described.

DESCRIPTION

FIG. 1 is a perspective view of a push-to-close latch showing my new design.

FIG. 2 is a bottom plan view of the push-to-close latch of FIG. 1.

FIG. 3 is a right side elevation view of the push-to-close latch of FIG. 1.

FIG. 4 is a top plan view of the push-to-close latch of FIG. 1.

FIG. 5 is a left side elevation view of the push-to-close latch of FIG. 1.

FIG. 6 is a front elevation view of the push-to-close latch of FIG. 1.

FIG. 7 is a rear elevation view of the push-to-close latch of FIG. 1.

FIG. 8 is a right side view of a push-to-close latch showing a second embodiment push-to-close latch of my new design. The left side view is identical.

FIG. 9 is a front elevation view of the push-to-close latch of FIG. 8. The rear view is identical.

FIG. 10 is a top plan view of the push-to-close latch of FIG. 8.

FIG. 11 is a right side view of a push-to-close latch showing a third embodiment push-to-close latch of my new design. The left side view is identical.

FIG. 12 is a front elevation view of the push-to-close latch of FIG. 11. The rear view is identical; and,

FIG. 13 is a top plan view of the push-to-close latch of FIG. 11.

The bottom views of the second and third embodiments are identical to FIG. 2.
